UNITED STATES PATENT OFFICE.

JACOB B. STRUBLE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRIC SIGNALING.

No. 849,170.

Specification of Letters Patent.

Patented April 2, 1907.

Application filed December 3, 1902. Serial No. 133,711.

To all whom it may concern:

Be it known that I, JACOB B. STRUBLE, residing at Wilkinsburg, in the county of Allegheny and State of Pennsylvania, a citizen of the United States, have invented or discovered certain new and useful Improvements in Electric Signaling, of which improvements the following is a specification.

The invention described herein relates to certain improvements in electric signaling, and has for its object the utilization of alternating currents or interrupted, fluctuating, or pulsating direct currents for controlling by a home signal its distant signal without the use of line or equivalent wires when such currents are used in a track-circuit between them. As a distant signal and a home signal when at the same signaling-point and controlled from the same track-circuit must at times give different indications, provision must be made for a selection to be automatically effected by a succeeding home signal. When using alternating or equivalent currents, the necessary selection may be effected by making a change in the current in the track-circuit—for example, changing a characteristic or the relation of the factors of the alternating current in the circuit. Hence, as regards the broad claims herein, the terms thereof are not limited to either the specific change or manner of changing nor to any specific form or construction of apparatus employed therefor.

The invention is hereinafter more fully described and claimed.

In the accompanying drawings, Figure 1 is a diagrammatic view of a portion of a railway, showing an arrangement of signals for controlling the several track or block sections. Fig. 2 is a diagrammatic view of two track or block sections and home and distant signals therefor arranged in pairs on posts and the mechanism and circuits for operating and controlling said signals and embodying my invention. Fig. 3 is a view similar to Fig. 2, showing one of the sections occupied and the signals indicating such condition. Fig. 4 is a diagrammatic view illustrating a modification of my improvement. Figs. 5 and 6 are detailed views.

Similar reference characters designate corresponding parts in all of the figures.

In the practice of my invention one of the line of rails, as 1, is made electrically continuous, while the other line of rails is divided into sections of suitable length, such sections being generally termed "track" or "block" sections. Insulation is provided between adjacent ends of rails at the ends of each section, as is the usual practice. 2 and 3 designate two such sections. At the entrance end of each of these track or block sections I arrange a home and a distant signal on the same support, the home signal indicating the condition of the section at the entrance of which it is placed and the distant signal indicating the position of the home signal for the next succeeding section, except when both signals are simultaneously put to "danger" by a train entering a block-section.

An alternating-current generator 6 has one of its terminals connected to the continuous rail 1, while its other terminal is connected to a feed-wire 7, extending along the track. The primary 8 of a transformer A has its terminals connected to the continuous rail 1 and the feed-wire 7. The secondary 9 of this transformer has one terminal connected to the continuous rail 1 and its other terminals 80 to contact-plates 10 and 11, one of which is intermediate of the ends of the transformer. These plates form parts of a switch or other circuit-controlling device, the other part thereof being formed by a movable member 85 12, adapted to be shifted by the home signal 4 of the section 3 from one contact-plate to the other. The lever or movable member 12 is connected, preferably, through a resistance 13 to the block or section rail 2. The employment of the resistance is desirable, as it will prevent an excessive flow of current from the secondary of the transformer A to the track when short-circuited by a train on section 2. At the entrance end of block-section 2 the continuous rail 1 and sectional rail of the block-section are connected to a translating device for controlling or operating the home and distant signals 4 and 5, said translating device being so constructed and proportioned that when the alternating current of the track-circuit is changed or modified it will respond or operate to control only one of the two signals 4 5, but when the alternating

current of the track-circuit is normal or usual the translating device will respond or operate to control both of the signals 4 and 5. In the construction shown in Fig. 2 the translating device is shown as comprising two relays 14 and 15 and as being connected either in multiple or series with the circuit of the secondary of the transformer 9. When the relays are liable to be effected by foreign influences, 10 as direct currents in the track-circuit, it is preferred to interpose a suitable transformer or equivalent device 16, the relays being arranged in the circuit of the secondary of such transformer. The secondary of the transformer 9 of track-rails 1 and 2 and the translating device or devices constitute a track-circuit, which is shown as a closed track-circuit. Each track or block section is provided with a similar track-circuit.

20 The operating mechanisms 17 and 18 of the signals may be any of the well-known types which comprise an electrically-operated device for controlling the motive power for the mechanisms, and such electrically-operated devices are arranged in circuits controlled by the armatures of the relays 14 and 15, said circuits, by preference, including the secondary of a transformer 19. The primary of this transformer has its terminals 25 connected to the continuous rail 1 and the feed-wire 7. When the home signal of any block-section is in its clear position of indication, the member 12 is so shifted that the full voltage of the secondary of transformer A is supplied to the track-circuit of the preceding block-section, thereby exciting both relays 14 and 15 and closing the motor-circuits of signals 4 and 5, whereupon both signals are cleared. As soon as a train passes into a 30 block-section both the home and distant signals at the entrance thereof will go to "danger." The home signal moving to "danger," (for example, the home signal 4^a of block-section 3 when a train enters block-section 3,) the member 12 will be moved into contact with plate 10, cutting out a portion of the secondary of the transformer A and reducing the voltage in the track-circuit of block-section 2 to such an extent that relay 35 15 of that track-circuit will not be energized to close the circuit of the distant signal 5, so that the latter will be held in its caution position of indication, which is an advance indication of the position of home signal 4^a. The relay 14 of any track-circuit is so constructed in the form of invention of Figs. 2 and 3 as to be operative not only when the full voltage of transformer A is on the track-circuit, but also when such voltage is reduced by the 40 shifting of the movable member 12 to the contact 11, while relay 15 of any track-circuit will be responsive only to the full voltage of the secondary of the transformer A.

45 In order to prevent a false movement of a home signal which is located on the same

post with a distant signal, as the movable member 12 of the switch passes from contact-plate 10 to plate 11, and vice versa, provision is made, as by employment of two fingers 20 on the movable member, (see Fig. 5,) 75 and connected through a resistance 21, so that the movable member will contact with plate 10 before it leaves plate 11, and vice versa. A single finger sufficiently wide to contact simultaneously with both plates cannot be used, as the included portion of the secondary would in such case be short-circuited. In order to prevent a momentary interruption of the current-supply to the track-circuit at the latter part of the shifting 80 movement, the contact-plates are so constructed with reference to the space between the fingers 20 that both fingers will contact with the plates until the member 12 is fully shifted. If desired, an overload voltage-regulator 22 may be employed to open the circuit of the generator 6 should the voltage become excessively high.

In the construction shown in Fig. 3 the electrically-operated device of the mechanisms 17 and 18 of the signals 4 and 5 are connected to the track-circuit so as to be operated directly by changes in the track-circuit. If desired, a transformer 16 may be employed to prevent the electrically-operated device being effected by disturbing influences. It will be understood, of course, that the electrically-operated device will be constructed to respond to the changes in the track-circuit.

In lieu of adjusting or changing the secondary of the transformer the change in the ratio of the transformer may be made in the primary winding, for the reason that if a given voltage be impressed on a portion of the turns of the primary of a transformer a higher voltage will be given off the secondary than when a like voltage is impressed on all the turns of the primary. In carrying out this construction the contact-plates 10^a and 11^a are so connected to the primary of the transformer that when the signal 4^a is cleared a portion of the primary is cut out, and hence a higher voltage will be given off the secondary of the transformer onto the track-circuit 115 2, thereby causing both signals 4 and 5 to go to "clear." This arrangement of the primary is illustrated in Fig. 4. When signal 4^a goes to "danger," the movable member 12 will contact with plate 11^a and voltage will be impressed on all the turns of the primary, so that only sufficient voltage will be given off the secondary of the transformer to effect or permit of the movement of the distant signal 5 to "caution."

In lieu of employing two relays for controlling the circuits of the signals 4 and 5 a single mechanism operating on the shifting-field principle may be employed. Such a mechanism is shown in Fig. 4 and performs 120 125

all the functions of the two relays in Fig. 1. This mechanism, (translating device,) or, as I shall hereinafter term it, "relay," has a core 24, formed of laminated iron, and a coil 25, which is connected to the continuous rail 1 and the sectional rail of a block-section. The core and coil constitutes a field. The poles or ends of the cores are slotted to form fingers 26 and 27, and one of the fingers, as 5 10 15 20 25 30 35 40 45 50 55 60 65 70 75 80 85 90 95 100 105 110 115 120 125 130

one of each pole is surrounded by a closed circuit 28. A disk 29, formed of electric conducting and preferably non-magnetic material and constituting an "armature," as I shall hereinafter term it, is pivotally mounted in operative relation to the core, so as to move freely between the poles, and is adapted to be shifted in one direction by electric energy and in the opposite direction by any suitable power, as gravity. Movable contact-fingers 30 and 31 are connected to the armature so as to be shifted into and out of contact with the plates 32 and 33, thereby closing and opening the circuits of the motors of signals 4 and 5.

25 The armature 29 has a portion adjacent to the poles of the core cut away, so as to reduce the area affected by the currents from the track-circuit. When the circuit of block-section 2 is short-circuited by the presence of 30 a train, so that no alternating current from the track will pass through the field of the relay, the armature will drop against a stop 34, thereby shifting the fingers 30 and 31 out of contact with the plates 32 and 33. As soon 35 as a train enters block-section 3 and the signal 4^a goes to "danger" the movable member 12 of the switch device will be brought into contact with the plate 11^a, so that voltages will be impressed upon all the turns of 40 the primary of the transformer A and relatively low voltages will be given off as a consequence thereof from the secondary of said transformer. By reason of the voltages in the track-circuit flowing through the field a shifting magnetic field will be established, 45 due to the electric and magnetic effect of the closed circuits 28 on sections or fingers of the poles of the core. By reason of this shifting field the armature will be raised an amount sufficient to bring the offset due to the cutting away of a portion of the disk to the lower 50 edge of the pole-pieces. A further effective movement will not be produced by reason of the reduced effective area of the disk between the pole-pieces. When the train passes 55 off of section 3 and the signal 4^a goes to "clear," the movable member 12 of the switch will be shifted into contact with the plate 10^a, thereby cutting out a portion of the primary of the transformer A, so that increased 60 voltages will be given off of the secondary of the transformer and transmitted along the track-circuit to the field of the relay, causing the armature 29 to have additional movement against the stop 35. When the arm-

ture is in intermediate position, as above described, the finger 30 will contact with the plate 33, closing the circuit through signal 4 of block-section 2; but when the armature is raised to full position, as above stated, due to the clearing of signal 4^a, finger 31 will contact with its plate 33 and close the circuit of signal 5, thereby causing such signal to go to clear position.

While I have described with some particularity a specific form of apparatus for selecting the characteristic of current to be used for operating the particular signal, the invention as regards the terms of the broad claims is not limited to any particular method of or apparatus used to accomplish the selection on account of the great number of forms and arrangements which such apparatus may assume.

It is obvious from the foregoing that an almost endless variety of arrangements of apparatus which is operated selectively, due to variations in the voltage, frequency, and phase relation, can be employed, and it is within the knowledge of one skilled in the art to readily specify one for the other.

Under the term "signal-controlling mechanism" is included not only a construction wherein the electrically-operated devices of the signal mechanism are directly in the track-circuit, but also a construction wherein the electrically-operated devices are in independent circuits, which are controlled by relays or other mechanisms included in the track-circuit.

100

Having thus described my invention, what I claim is—

1. The combination with a track-circuit for signaling purposes, of an alternating-current supply therefor, a translating device responsive to alternating current in said circuit and unresponsive to a modification of the alternating current and means for modifying the alternating current.

2. The combination with a track-circuit for signaling purposes, of a source of alternating-current supply, a translating device responsive to an alternating current in said circuit and unresponsive to a modification of the alternating current, and means for modifying the alternating current.

3. The combination with a track-circuit for signaling purposes, of an alternating-current supply, a translating device responsive to the alternating current in said circuit and unresponsive to a modification of the alternating current, means for modifying the alternating current, and means for preventing direct current effectively operating the translating device.

4. A signaling system having in combination a series of track-sections each comprising a track-circuit, an alternating-current supply for each track-circuit, a translating device for each track-circuit, signals for the track-sec-

125

130

tions having operating mechanisms, and means for modifying a characteristic of the alternating current in a track-circuit.

5. In combination, two track-sections, each comprising a track-circuit including a source of alternating current and a translating device which is responsive to the usual alternating current of the track-circuit to control one operation of both a home and distant signal and responsive only to control the home signal when the usual alternating current of the track-circuit is changed, a home and distant signal for each track-section, and means operated by a home signal when moving to its danger position for changing the alternating current in the track-circuit controlling its distant signal, whereby the translating of that track-circuit will be unresponsive to control the distant signal.
10. 6. In a signaling system, the combination of a series of track-sections each comprising a track-circuit, a source of alternating current for each track-circuit, a home signal and operating mechanism for one track-section, a distant signal and operating mechanism at a preceding track-section, a translating device in each track-circuit for controlling the operation of each signal-operating mechanism, and means for changing a characteristic of the alternating current in the track-circuit for the distant signal to render the translating device of that track-circuit responsive and unresponsive thereto.

7. In a signaling system, the combination of a series of track-sections each comprising a track-circuit, a source of alternating current for each track-circuit, a home signal and operating mechanism for one track-section, a distant signal and operating mechanism at a preceding track-section, a translating device in each track-circuit for controlling the operation of each signal-operating mechanism, and means operated from the home signal for changing the alternating current in the track-circuit of the distant signal to render the translating device of that track-circuit responsive and unresponsive thereto to control the home and distant signals.

8. In a signaling system, the combination of a series of track-sections each comprising a track-circuit, a source of alternating current for each track-circuit, a home signal and operating mechanism for one track-section, a distant signal and operating mechanism for the home signal at a preceding track-section, a translating device in each track-circuit for controlling the operation of each signal-operating mechanism, and means in each track-circuit for preventing the effective operation of a translating device by any direct current in the track-circuit.

9. In a railway signaling system, the combination of a series of track-sections each comprising a track-circuit, a source of alternating current for each track-circuit, a home

and distant signal located at the entrance of each track-section and each signal provided with an operating mechanism, a translating device in each track-circuit for controlling circuits for the operating mechanisms of the signals, said translating device being responsive in its action to the alternating current in the track-circuit to control the circuits of both operating mechanisms and responsive to a change in the alternating current in the track-circuit to control the circuits of one of the operating mechanisms, and means for changing the alternating current in the track-circuit.

10. In a railway signaling system, the combination of a series of track-sections each comprising a track-circuit, a source of alternating current for each track-circuit, a home and distant signal located at the entrance of each track-section, and each signal provided with an operating mechanism, a translating device in each track-circuit for controlling circuits for the operating mechanisms of the signals, said translating device being responsive in its action to the alternating current in the track-circuit to control the circuits of both operating mechanisms and responsive to a change in the alternating current in the track-circuit to control the circuits of but one of the operating mechanisms, and means operated by a home signal of one track-section for changing the alternating current in a preceding track-circuit.

11. In a signaling system, the combination with a home signal, a track-circuit including a source of alternating current and a relay responsive to the alternating current for controlling the home signal, a distant signal for the home signal, a track-circuit including a source of current, a relay responsive to the current from said source for controlling the distant signal, and means under the control of the track-circuit for the home signal for changing the alternating current in the track-circuit for the distant signal to which change in current the relay is not responsive.

12. In a signaling system, the combination with a home signal, a track-circuit including a source of alternating current and a relay responsive to the alternating current for controlling the home signal, a distant signal for the home signal, a track-circuit including a source of current and a relay responsive to the current from said source for controlling the distant signal, and means under the control of the track-circuit for the home signal for effecting the source of current in the circuit for the distant signal whereby its relay will or will not respond to control the distant signal.

13. The combination with a plurality of railway-signals located alongside a railway-track, apparatus for controlling the said signals which is selectively responsive to a current characteristic consisting in a periodic

- variation to control one signal and also controllable by electric current to perform another operation, and means for producing the current of periodic characteristic and the 5 current for effecting the second operation, such apparatus being controllable by the current-producing means through suitable current-transmitting means including a conductor common to the current of periodic 10 characteristic and the current for effecting the second operation.
14. In a block-signal system, the combination with track-circuit sections and signals for said sections; of a source of energy connected at one end of each of said sections; a relay connected to the other end of each of 15 said sections, comprising a stationary field and a rotating armature capable of three functional positions; means for controlling the functional positions of said armature; and means for making said signals give indications corresponding to the said three positions of said armature.
15. In a block-signal system the combination with track-circuit sections and signals for said sections; of a source of energy connected at one end of each of said sections; a relay connected at the other end of each of 20 said sections, comprising a stationary field and a rotating armature capable of three functional positions; means for controlling the functional positions of said armature; and means for controlling one of said signals by one of said functional positions of said armature; and means for controlling two of said 25 signals by another functional position of said armature.
16. In a block-signal system, the combination with track-circuit sections and signals for said sections, of a source of energy connected to one end of each of said sections, a relay connected at the other end of each of 30 said sections comprising a stationary field and a rotating armature capable of three functional positions, means for controlling 35
17. In a signaling system for railways, the combination with block-sections, a home and distant signal for each block-section, a source of alternating current and a relay for each block-section, said relay comprising a field and an armature having three functional positions, each of which positions effects a control of one or both of the railway-signals. 40
18. In a signaling system for railways, the combination with block-sections, a home and distant signal for each block-section, a source 45 of alternating current and a relay for each block-section, the relay comprising a field and an armature capable of three positions in each of which positions a control of one or both of the signals is effected, and means controlled by a home signal for producing changes in the alternating current to cause the armature to assume two of its three positions. 50
19. The combination with a relay for controlling a plurality of signals comprising a field and an armature, the latter having a plurality of functional positions in each of which one or more signals are controlled, and said armature movable to two of its positions 55 by an alternating current and a change of characteristic thereof, and means for supplying the alternating current to the relay and changing a characteristic thereof.
- In testimony whereof I have hereunto set 60 my hand.
